UNITED STATES PATENT OFFICE

157,049

COVERED WASHSTAND

Basil E. Jones, Flossmoor, Ill., assignor to Pullman-Standard Car Manufacturing Company, a corporation of Delaware

Application December 29, 1948, Serial No. 150,422

Term of patent 14 years

(Cl. D4—2)

To all whom it may concern:

Be it known that I, Basil E. Jones, a citizen of the United States, residing at Flossmoor, in the county of Cook and State of Illinois, have invented a new, original, and ornamental Design for Covered Washstand, of which the following is a specification, reference being had to the accompanying drawings, forming part thereof.

In the drawings—

Fig. 1 is a general perspective view of my new design for a covered washstand arrangement showing the washstand with the cover thereof in closed position;

Fig. 2 also is a general perspective view of the washstand arrangement but showing the washstand with the cover thereof in open position;

Fig. 3 is a top plan view of Fig. 2 partly in section taken on a plane as indicated by the line 3—3 of Fig. 2;

Fig. 4 is a top plan view of Fig. 1 partly in section taken on a plane as indicated by the line 4—4 of Fig. 1; and

Fig. 5 is a sectional view through the washstand taken along the line 5—5 of Fig. 2 showing the contour of the bowl portion of the washstand and the stand portion.

The dotted line representations in the several figures of the drawings are for illustrative purposes only.

What is claimed is:

The ornamental design for a covered washstand, substantially as shown and described.

BASIL E. JONES.
